UNITED STATES PATENT OFFICE

PAUL ESCOLE, OF JEUMONT, FRANCE, ASSIGNOR TO ATELIERS DE CONSTRUCTION & FONDERIES DE JEUMONT, OF JEUMONT, FRANCE, A FRENCH SOCIETE ANONYME

GLASS SHEET DRAWING APPARATUS

Application filed December 12, 1928, Serial No. 325,454, and in France May 5, 1928.

This invention relates to apparatus for drawing glass in sheets by means of movable rollers.

These apparatus generally comprise rollers 5 mounted on horizontal axes and juxtaposed in pairs. In each pair, one roller is driven by external means, its axis being fixed, and this roller transmits its movement by means of gears to the other or driven roller, of 10 which the axis can be displaced. Thus a variable separation can be obtained between the rollers of a single pair. The necessary pressure of the second roller against the first or driving roller is ensured by levers and 15 counterweights.

The invention has for its principal object to improve and render more sensitive the suspension of the driven rollers of the apparatus.

20 Another object is to provide for driving the rollers by a flexible connection with the driving means, allowing the suppression of the gear wheels with long teeth which are usually employed for transmitting movement 25 from the one roller to the other of each pair and in order to accommodate the variable separation of the two rollers. In accordance with the invention, these rollers are fitted with bearing bushes of spherical external shape 30 at their middle, in which the trunnions of the said rollers can revolve without possible wedging. Knife edge supports are arranged on the inter-section of the two arms of bell crank levers supporting the bearing bushes 35 in such a way that the levers can oscillate, following the movements of the rollers with the minimum of resistance, one extremity of each bell crank lever constituting the bearing for the roller trunnion.

40 The rollers are driven by means of an elastic connection with the driving means, allowing the suppression of gear wheels with long teeth.

In order to facilitate the understanding 45 of the invention, there is represented upon Figures 1 to 3 of the accompanying drawings a glass-drawing apparatus constructed in accordance with the invention.

50 Figure 1 is an elevation of the apparatus. Figure 2 represents the device ensuring

the pressure of the driven roller against the juxtaposed driving roller, as seen from the opposite end of the apparatus.

Figure 3 is a plan corresponding to Figure 2 showing also the flexible means for driving 55 the rollers.

Figure 4 shows on a larger scale the inclined position which the trunnion of the driven roller can take up in its bearing block.

Figure 5 shows also on a larger scale the 60 novel method of suspension of the lever controlling the pressure of the driven roller against the juxtaposed driving roller.

In these drawings, 1 is the driving roller and 65 2 is the juxtaposed driven roller. The rollers 1 and 2 (Figure 3) rest by means of their trunnions 1', 2' respectively in suitable bearing bushes 16 and 18. The bushes 16 are carried by the frame of the apparatus and the bushes 18 are mounted externally of the 70 frame in a kind of bearing block 17 formed by one end of a bell crank lever 19 (Figure 2). Naturally suitable openings 13 are provided in the frame 14 in order to allow the free passage of the trunnions of the rollers 2. 75

The lever 19 carries at its other extremity an adjustable counter-weight 12. The five pairs of rollers 1 and 2, represented in Figure 1, are arranged in the same manner and at suitable distances vertically from one another. 80

The objects in view are obtained by means of the following devices:—

(1) The trunnions 2' of the roller 2 revolve 85 in bearing bushes 18 of spherical external shape at their middle parts 18' and adapted to rock or roll in the bearing blocks 17 constituted by one end of the bell crank levers 19; see Figure 3 and more particularly Figure 4. 90

It will be understood that this arrangement allows the trunnions always to place themselves in a suitable way whatever be their inclination, which obviates any wedging of the trunnions in their bearing bushes upon the 95 passage of a foreign body. It results from this arrangement that the high supplementary resistance opposed by this fact in the usual apparatus is never manifested.

(2) Each bell crank lever 19, instead of 100 presenting a hinge such as that of an ordinary

bell crank lever comprises at the intersection of its two arms a gap or opening 19' (see Figure 5), of which the section has the form of a circular sector, into which there is introduced a knife-edge 20 mounted upon a smaller sector shaped support 20' fixed on the frame. It will be understood that this extremely sensitive suspension allows the bell crank lever 19 to oscillate upon the knife-edge 20, according to the displacements of the driven roller 2, opposing the minimum resistance to these movements.

(3) The vertical driving shaft 21 (Figure 3) is mounted upon a separate support 28 placed at a certain distance from the apparatus proper, and the transmission is effected by the intermediate parts which will be described hereafter.

The support 28 is traversed by horizontal shafts 24 and 27 situated in the same plane, and substantially in line with the rollers 1 and 2 respectively.

The shaft 24 is driven by the shaft 21 by means of bevel toothed wheels 22, 23, and it drives the shaft 27 by means of two wheels 25 and 26 of fine tooth-pitch, arranged on the opposite side of the support 28.

The shafts 24 and 27 respectively transmit their movement to the trunnions of the rollers 1 and 2 by intermediate shafts 29, 30; these latter are connected at each end by universal joints 31, on one hand to the shafts passing through the support 28 and on the other hand to the trunnions of the rollers.

It is possible, evidently, to substitute for the intermediate shafts 29 and 30 and the joints 31, either very flexible rods, assembled in any suitable way, for example by caps fitted over the ends of the parts to be connected, or other flexible connecting means.

It will be understood that this novel method of driving allows the suppression of gear wheels with long teeth and the disadvantages inherent in these devices.

The present arrangement ensures smooth and regular rotation of the rollers; consequently the causes of breakage are very much reduced.

Moreover, the expansion of the apparatus under the influence of heat can take place in all directions, without interfering with the manufacture, by reason of the utilization of flexible intermediate members for the transmission of the drive.

Lastly, the apparatus is rendered more accessible by the separation of the gear wheels from the frame 14; windows and inspection doors 15 can in fact be placed level with each pair of rollers without being interfered with by the mechanism.

The apparatus described operates in the same way as the ordinary apparatus, but it will be noted that if a foreign body such as 32, Figure 3, is introduced between two juxtaposed rollers, then as a result of the improve-

ments described above, the roller 2 moves easily away from the roller 1, the resistances to be overcome being reduced to the minimum, and the pressure exerted at 33 increased only slightly compared with the normal pressure. As soon as the foreign body 32 escapes from the rollers 1 and 2, the roller 2 comes without delay to press again upon the sheet for the whole of its width. Consequently the passage of the foreign body causes only an insignificant disturbance of short duration.

The construction described above is given only by way of example; it is evident that the arrangements previously enumerated may be applied to all machines of the Foucault type for drawing glass. It is in fact permissible without exceeding the scope of the invention to arrange the constituent elements of the novel improved apparatus in such a way as to obtain modifications behaving in practice in the same manner as the example described.

What I claim is:—

1. In glass sheet drawing apparatus including a pair of rollers and means for pressing said rollers against opposite faces of the sheet, a suspension device for the movable roller, comprising a bearing bush for the trunnion of said roller, a bearing block through which pressure is exerted upon said trunnion, and a spherical seating of said bush within said bearing block.

2. In glass sheet drawing apparatus, including a pair of relatively movable rollers and means for pressing said rollers against opposite faces of the sheet, a suspension device for the movable roller, comprising a weighted bell crank lever, a fixed pivot for said lever, and a bearing bush for the trunnion of said roller, said bearing bush having a spherical seating within one arm of said bell crank lever.

3. In glass sheet drawing apparatus, including a pair of relatively movable rollers and means for pressing said rollers against opposite faces of the sheet, a suspension device for the movable roller, comprising a bell crank lever, a knife edge pivot for said bell crank lever, said knife edge being fixed upon the frame of the apparatus at the point of intersection of the two arms of said bell crank lever, and a bearing bush for the trunnion of said roller, said bush having a spherical seating in the extremity of one of the arms of said bell crank lever, and the other arm of said lever being weighted to press said rollers together.

4. In glass sheet drawing apparatus, including a pair of relatively movable rollers and means for pressing said rollers against opposite faces of the sheet, a suspension device for the movable roller, comprising a bell crank lever, a fixed pivot for said lever, a bearing bush for the trunnion of said roller, said bush being flexibly mounted in said bell crank lever, a pair of intermeshing gears

mounted at fixed centers, and flexible driving connections between the trunnions of said rollers and said intermeshing gears.

5. In glass sheet drawing apparatus, including a pair of relatively movable rollers and means for pressing said rollers against opposite faces of the sheet, a suspension device for the movable roller, comprising a bell crank lever, a fixed pivot for said lever, a bearing bush for the trunnion of said roller, said bearing bush having a spherical seating within one extremity of said lever, and a pair of intermeshing gears mounted at fixed centers for driving said rollers, each of said 15 gears being flexibly connected to the respective roller by an intermediate shaft having universal joints at its extremities connecting with the gear and roller.

In testimony whereof I hereunto affix my
20 signature.
